US00D752562S

(12) **United States Design Patent**
You

(10) **Patent No.:** US D752,562 S
(45) **Date of Patent:** ** Mar. 29, 2016

(54) **ROUTER**

(71) Applicant: **Huawei Device Co., LTD**, Shenzhen (CN)

(72) Inventor: **Xiaoyu You**, Wuhan (CN)

(73) Assignee: **Huawei Device Co., Ltd.**, Shenzhen (CN)

(**) Term: **14 Years**

(21) Appl. No.: **29/480,548**

(22) Filed: **Jan. 27, 2014**

(30) **Foreign Application Priority Data**

Jul. 27, 2013 (CN) 2013 3 0356711

(51) **LOC (10) Cl.** **14-03**

(52) **U.S. Cl.**

USPC **D14/240**

(58) **Field of Classification Search**

USPC ..... D14/135, 137, 139, 140-140.9, 155, D14/167, 240, 242, 243, 348, 349, 351, 354, D14/355, 356, 357, 358, 385, 433, 435, D14/435.1, 436, 474, 480, 496, 107, 108, D14/138 G; D13/103, 108, 110, 147; D10/75

(57) **CLAIM**

The ornamental design for a router, as shown and described.

DESCRIPTION

FIG. 1 is a bottom view of a router;

FIG. 2 is a top view thereof;

FIG. 3 is a right side view thereof;

FIG. 4 is a front view thereof;

FIG. 5 is a left side view thereof;

FIG. 6 is a back view thereof; and,

FIG. 7 is a front perspective view thereof.

The broken lines shown in the figures that are immediately adjacent to the shaded areas and define unshaded regions represent the bounds of the claim, while all other broken lines show environment subject matter; the broken lines form no part of the claimed design.

The “logo” shown in the drawing disclosure is a registered trademark of Huawei Device Co., LTD, Shenzhen CHINA.
